CLAIM

The ornamental design for a plastic bag rack, as shown and described.

DESCRIPTION

FIG. 1 is a side elevational view of a plastic bag rack showing my new design, the opposite side being a mirror image of that shown;

FIG. 2 is a front elevational view thereof;

FIG. 3 is a rear elevational view thereof;

FIG. 4 is a top plan view thereof;

FIG. 5 is a bottom plan view thereof;

FIG. 6 is an enlarged fragmentary sectional view taken along line 6—6 of FIG. 1;

FIG. 7 is an enlarged fragmentary sectional view taken along line 7—7 of FIG. 3;

FIG. 8 is an enlarged fragmentary sectional view taken along line 8—8 of FIG. 4;

FIG. 9 is an enlarged fragmentary sectional view taken along line 9—9 of FIG. 1;

FIG. 10 is an enlarged fragmentary sectional view taken along line 10—10 of FIG. 4; and

FIG. 11 is an enlarged fragmentary sectional view taken along line 11—11 of FIG. 3.

FIG. 1

FIG. 2

FIG. 3

FIG. 4

FIG. 6
